STEEL AND CONCRETE CONSTRUCTION

William A. Wilson, Canonsburg, Pa., assignor of
three-fourths to Frederick R. Wilson and one-
fourth to Elmer Leach, both of Canonsburg, Pa.

Application July 28, 1933, Serial No. 682,684

12 Claims.

(Cl. 72—71)

My invention relates to reinforced concrete construction and more especially to the reinforcement or steel work usable in floor construction, the present invention contemplating certain material changes or improvements on what is shown and described in my prior application for patent filed June 16, 1931, Serial No. 544,863.

The principal object of this invention is to provide steel reinforcing members for concrete construction work which can be readily and conveniently set in place to present an interlocking framework in the form of a grid made up of longitudinal and transverse trusses of different sizes in cross section, with the smaller trusses passing through the larger trusses and adapted to be spaced apart according to requirements relative to stress or load to be supported.

A further object of my invention is to provide a reinforcement for heavy-duty concrete floors comprising a steel framework or grid of truss through truss construction which is adapted to be employed in connection with a sheet metal base in the form of plates which are in some instances temporarily connected to the beams so as to be removable from the reinforced concrete floor and in other instances locked or firmly secured to the floor beams by a keeper rail welded thereon and upon which the truss through truss grid rests to be embedded in the concrete and form part of the floor structure.

With these principal objects in view my invention contemplates a particular arrangement of truss members having spaced apart longitudinal bars with separated webs whereby in the formation of the main or longitudinal trusses spaces are provided between the webs and bars for the passage of the transverse trusses of smaller size in cross section, the longitudinal truss members, in parallel series, being connected and braced together by metal clips engaging the lower longitudinal bars thereof, thus providing a grid-like steel structure for reinforcing a concrete floor either with or without a permanent sheet metal base, all as hereinafter described and specifically set forth in the appended claims.

In the drawings:—

Figure 1 is a plan view of a steel reinforcement for concrete floors constructed in accordance with my invention.

Fig. 2 is a plan view enlarged of a fragment of the reinforcement.

Figs. 3 and 4 are detail views illustrating the metal clip for connecting the longitudinal truss members.

Figs. 5 and 6 are sectional views on the lines 5—5 and 6—6 of Fig. 1.

Fig. 7 is a side elevation showing a modification of the truss members.

Fig. 8 is a sectional view on the line 8—8 of Fig. 7.

Fig. 9 is a side elevation illustrating the manner of supporting the steel reinforcement when used with concrete alone.

Fig. 10 is a similar view illustrating the employment of a sheet metal base.

Fig. 11 is a view showing the manner of nesting the truss members for transportation.

Fig. 12 is a plan view of the sheet metal plates forming the base of the floor construction.

Fig. 13 is a sectional view through the plates on the line 13—13 of Fig. 12.

Fig. 14 is a view of the plate retaining rail.

Fig. 15 is a sectional view thereof.

Fig. 16 is a sectional view enlarged showing the manner of connecting the base plates to the floor beams with the steel reinforcement above the same.

Figs. 17 to 22, inclusive, are modifications showing different forms of trusses that may be employed in constructing a grid-like reinforcement of truss through truss formation.

Figs. 23 and 24 show modifications of the clip for connecting the main trusses.

Fig. 25 is a plan view of a flat-truss reinforcement.

Fig. 25a is an enlarged sectional view thereof on the line 25a—25a of Fig. 25.

Fig. 26 is a plan view of a removable or temporary plate floor.

Fig. 27 is a sectional view illustrating the means for supporting the removable corrugated plates on which the concrete is poured.

Figs. 28 and 29 are modifications thereof.

Fig. 30 is a modification of the means for supporting the floor plate construction.

Figs. 31 to 34 illustrate further modifications of the temporary plate floor construction, and

Fig. 35 is an elevation showing a modification of the spacing means in the form of a spacing bar.

In the construction of the truss through truss grid-like form of reinforcement the longitudinal and transverse frame members or units may be similar in construction, each consisting of three bars spaced apart triangular in cross section and connected by rods bent into V-shape to provide webs at opposite sides of the truss, said webs in some instances extending transversely of the main bars while in other instances they extend longitudinally, as shown in the drawings, and this reinforcement for the concrete flooring is usable in connection with temporary or removable forms, as provided for in Figs. 26 to 34 inclusive, or permanent base plates as shown in Fig. 10.

In Figs. 1 to 6, inclusive, the longitudinal trusses are each made up of a main upper bar 20 and spaced apart lower bars 21, 21 connected by webs 22, the bent rods forming the webs extending directly between the bars at opposite sides of the truss and are spaced apart according to the strength of truss required leaving spaces between

them to receive the transverse trusses. The transverse trusses are similar in construction to the longitudinal trusses, that is to say comprise an upper main bar 23 connected to the spaced 5 apart lower bars 24, 24 by webs 25, and for the purpose of constructing the grid-like concrete reinforcement the trusses of one series, as the transverse trusses, are smaller in cross section than those of the other series so they can be slid 10 through the same between the webs to rest on the lower bars. The transverse trusses may be located in alternate spaces or wherever required according to disposition of the stress to which the floor will be subjected; in other words, at certain 15 portions of the grid forming the steel reinforcement the transverse trusses may be located closer together than at other portions thereof.

The formation of the trusses or reinforcement units permit them to be shipped nested, as shown 20 in Fig. 11, and in constructing the grid the longitudinal trusses are connected together in parallel series by means of metal clips 26 engaging the contiguous lower bars 21, 21, the purpose of the clips serving more especially to bind the 25 trusses together rather than increase the strength of the reinforcement inasmuch as any load on the top bars of these trusses tends to press the bottom bars outwardly or the bars of one truss towards the bars of the adjoining truss neutralizing the 30 action of one by the other. The special form of clip is illustrated in Figs. 4 and 5, from which it will be noted that the strip of spring steel is bent semi-circular in shape at both ends to embrace the bars and clamp them closely together, the bent 35 end portion 26a being in the arc of a circle corresponding with that of the circumference of the bar, while the arc of the bent end portion 26b is slightly less than that of the circumference of the companion bar so that the last mentioned end 40 portion will be sprung over the bar by the tap of a hammer. The clips remain in place to be embedded in the concrete and although they are permanently attached and consequently seldom required to be removed the bent end portion 26b 45 terminates in an outwardly projecting loop 26c that may be gripped by pliers should it be desired to remove the clip.

It will be apparent that by the use of different 50 size truss members of the construction hereinbefore described the work of forming a net work of steel reinforcement for all kinds of floors can be accomplished expeditiously for the reason that it is necessary only to set the longitudinal trusses and after locking them by means of the clips pass 55 the transverse trusses through the spaces intermediate the webs, and in joining a series of transverse trusses with another series they are lapped as shown in Fig. 2—the ends of one series being interposed between the ends of the other series 60 to rest upon the lower bars of two adjoining longitudinal truss members. As will be understood the size of the metal bars and rods forming the truss members may be varied to suit the strength of floor desired, and in these as well as other respects my invention provides a wide latitude or 65 variety in construction.

It is essential that the webs of the larger truss 70 members should be arranged so as to provide the required spaces for the passage of the smaller truss members, but instead of having the webs or rods extend directly from the upper to the lower bars, as hereinbefore described, they may be disposed as illustrated in the modification Figs. 7, 8, 10 and 16, in which the webs extend diagonally at opposite sides of the truss between the 75

upper bar 27 and lower bars 28, 28 and on a line therewith. In this instance also the rods forming the webs 29 are bent V-shape with the ends extended to bear on the lower bars to which they are welded. This form of truss possesses advantages over the other form and consequently the smaller truss members are similarly constructed, the upper and lower bars 30 and 31, 31 being connected by diagonal webs 32, and of course the angle of the bent rods forming the webs 29 of the larger trusses is such as to provide spaces to receive the smaller trusses. In this instance also the lower bars 28, 28 are connected by clips 26 in constructing the grid-like reinforcement. In either instance, however, this type of deck or 10 floor reinforcement is very cheap for the reason that the truss members or units can be shipped economically and when assembled provides a mat of maximum strength consistent with the weight of steel employed. Furthermore, as the truss 20 members or units are easily handled in producing the net work with the longitudinal bars of the trusses crossing each other the assembly can be accomplished with greater facility by eliminating the expensive work of tying or welding loose 25 members, it being necessary only to lay the larger truss members so as to be supported at their ends on the floor beams and pass the smaller trusses through them, and it will be obvious that in the completed structure the load 30 carried by the top bars of the main trusses is transmitted through the webs to the bottom bars of said trusses and the load carried by the top bars of the smaller trusses carried likewise through the bottom bars thereof to the main 35 trusses upon which they rest.

Although different forms of bar construction may be used in providing the truss through truss construction those illustrated in Figs. 17 to 22 possess peculiar advantages in a structure of 40 this kind. In Fig. 17 the smaller or transverse trusses which extend through the webs 37 of the spaced apart bars of the main trusses 38 are formed of four longitudinal bars designated by the numeral 39 connected by a transverse web 40, 45 the longitudinal bars being arranged in upper and lower spaced apart pairs with the lower pair spaced at a greater distance apart than the upper pair and having the web 40 extending between the upper pair of bars beneath the same 50 and from the said bars to the lower pair respectively, while in Figs. 18 and 19 four longitudinal bars 41 are also employed but in this form the upper and lower pairs of bars are close together with the bent rod or web 42 welded between said 55 bars. The truss shown in Fig. 20 is a modification of the truss shown in Fig. 17, the four longitudinal bars 43 being spaced apart rectangular in cross section with the web 43a extending across the top of the upper pair of bars and from the latter downwardly to the lower bars. In each instance the webs are welded to the longitudinal bars, and it will be noted that these forms of smaller truss members are adapted for use in connection with main trusses in which the longitudinal bars are connected by vertical webs 45.

In Figs. 21 and 22 I have shown a form in which the web 46 extends from one of the lower longitudinal bars 47 diagonally to the upper longitudinal bar 48 and from the latter diagonally to the other lower bar, and in this instance also the rod forming the web is bent generally V-shape with the bent portion curved under the upper longitudinal bar to form a seat 49 for said bar in which it is welded. 75

In some instances it is desirable to space the longitudinal trusses apart to a more or less extent and in Figs. 23 and 24 I have shown modifications of the metal clip hereinbefore described, in Fig. 23 the bent end portions 50, 50 of the clip having the connecting portion 51 extended to permit the insertion of a bent or curved piece of metal or short bent bar 52 between the bars 21, 21, and in Fig. 24 the connecting portion 51 of the clip is longer for separating the bars of adjoining main trusses a greater distance apart, the clip being reinforced by means of a rail, bar or section 53. The modification shown in Fig. 25 illustrates the adaptation of the metal clips 26, hereinbefore described, in connecting flat bar trusses, each truss consisting of spaced apart longitudinal bars 57, 57 on a horizontal plane with each other and connected by webs 55 in the form of rods bent zig-zag between the companion bars 57. It is therefore obvious that the special form of metal clip is subject to modifications for connecting and spacing various forms of bar trusses in addition to those forms which provide for the truss through truss construction hereinbefore described, and instead of clips, spacing of the trusses may be effected by an inverted T-rail 75 having spaced apart notches 76 to receive the bars.

In the construction of a concrete floor it is oftentimes desirable that the plate floor or forms on which the concrete is poured be removed, and therefore it is an important part of my present invention to support the corrugated plates 35 from the floor beams 33 so that they may be easily placed in position and easily removed after the concrete is set. To accomplish this in the assembling of the floor plates they are suspended from the floor beams by means of U-bolts 60 of a width corresponding with the width of the upper end of the I-beam 61 on which the U-bolt rests so that the ends of said U-bolt will depend below the flanges of the I-beam at the outer edges thereof to receive metal strips or narrow plates 62 by which the metal plates 35 are supported between the floor beams, and to also receive diagonal braces 63 extending across the under side of said floor plates, said floor plates and braces being temporarily held in place by nuts 64, which when removed will permit the plate floor construction to drop away from the concrete leaving only the upper portion of the U-bolts embedded therein. It will be noted that in applying this plate floor construction to that type of I-beam in which the under side of the top flanges are inclined inwardly, as shown in Figs. 28 and 29, the supporting strip or narrow plates, as 65, for supporting the corrugated plates and braces at opposite sides of said I-beam are beveled at their upper inner edges to correspond with said flanges, and where the U-bolt is used on an end beam one leg of the bolt (66 in Fig. 29) is bent abruptly over the edge of the flange. Instead of using U-bolts I may employ plain bolts 67 as shown in Fig. 30, and in this instance also the bolts remain in place after the removal of the plates forming the temporary floor on which the concrete is poured.

It will be seen that in Fig. 26 the corrugated plates 35 are arranged with the corrugations extending transversely with respect to the floor beams 61 and rest at their ends on the narrow supporting plates 62 temporarily secured in place by the U-bolts, said corrugated plates being in overlapping sections as illustrated in Fig. 13, and where it is desired to lay the plates with the cor-

rugations extending longitudinally similar supporting plates 68 are employed of a width to accommodate any variations in the space between the floor beams 61, and in this modification the corrugated floor plates are supported intermediate the floor beams by angle bars 69, the bolts 60 extending over the I-beams passing through the supporting plates 68 and angle bars. Furthermore, where the construction of the floor embodies a stringer 72 extending between the floor beams I employ a supporting strip or narrow plate 70 bent laterally to extend from the floor beam 73 to the upper flange 72a between said flange and a supporting plate 71 temporarily supported from the stringer by U-bolts 60.

As hereinbefore stated the U-bolts are the only part of the removable plate floor construction which remains in the concrete floor, and of course this construction of removable floor plate is employed preferably with the truss through truss form of steel reinforcement.

The construction and arrangement of the truss members constituting the grid-like steel reinforcement hereinbefore described may be mounted on inverted T-rails interposed between said reinforcement and the supporting beams 33 to elevate the reinforcement above the I-beams between which the removable or temporary plate floor is built to support the concrete until it is set. However, in the construction of a heavy-duty deck or flooring, and wherever it is desired to have a metal base, a modification of the plate floor construction is employed in which the corrugated plates are locked or fastened to the floor beams by channel bars 36 extending along the floor beams and are provided with side flanges or lips 36b under which the ends of the plates are locked in the manner hereinabove described. These channel bars are welded to the beams, for which purpose the bottoms are provided with holes or slots 36a, and in building the plate base forming part of the reinforced concrete flooring one of said channel bars is welded upon a beam and after slipping an edge of the plate under the flange or lip at one side thereof the other edge of said plate is placed to rest on the next floor beam, and when a series or line of plates has been laid to extend the length of the attached channel bar another channel bar is welded to the second floor beam so as to overlap the edges of the plates, this operation being repeated to complete the floor area. In laying the plates either temporarily or permanently the bulged portion at the side of one overlaps the bulged portion at the side of an adjoining plate forming a tight joint in constructing the permanent floor and a tight joint is formed where the plates join the channel bars, thus providing a surface to receive the concrete which will prevent losses of fines.

By the particular construction of steel reinforcement in connection with either form of plate floor I provide an arrangement that will greatly facilitate the construction of floors for buildings, decks, and various other structures in the nature of a reinforced concrete slab, and as hereinbefore stated the reinforcement members or units permit of a disposition of the truss through truss grid or mat to meet various requirements as to design as well as stress of the load to be supported.

I claim:

1. A metal reinforcement for concrete decks and floors comprising truss members of different sizes in cross section, the larger truss members consisting of upper and lower bars spaced apart

- triangular in cross section and webs connected to said bars at opposite sides of the truss, said bars and webs being spaced apart to receive the smaller truss members through them at an angle thereto.
2. A metal reinforcement for concrete decks and floors comprising longitudinal truss members having upper and lower longitudinal bars spaced apart and connected by webs also spaced apart from each other leaving transverse openings between the bars and webs, together with transverse truss members of similar construction and smaller in cross section so as to pass through the openings in the first mentioned truss members, the smaller truss members presenting spaced apart lower bars which rest upon the lower bars of the larger truss members to reinforce the metal structure.
3. A metal reinforcement for concrete decks and floors comprising longitudinal and lateral truss members of different sizes, each truss member consisting of upper and lower horizontal bars spaced triangular in cross section and webs connecting said bars at opposite sides of the truss, the horizontal bars and webs of the larger truss members being spaced apart to receive the smaller truss members between them to provide a truss through truss form of reinforcement.
4. A metal reinforcement for concrete decks and floors comprising longitudinal and transverse truss members of different sizes, each consisting of upper and lower horizontal bars connected by webs at opposite sides of the truss, the webs of the larger truss members being in the form of short rods bent V-shape with the ends extended to rest upon the lower bars of the truss, said upper and lower bars and webs of the longitudinal or main truss members being spaced apart to receive the smaller or lateral truss members between them.
5. A metal reinforcement for concrete decks and floors comprising longitudinal and lateral truss members of different sizes in cross section forming a truss through truss construction, each truss member consisting of upper and lower horizontal bars spaced triangular in cross section with two of the bars lowermost and on a horizontal plane with each other, and webs connected to the triangularly spaced bars at opposite sides of the truss member, the horizontal bars and webs of the larger truss members being spaced apart to receive the smaller truss members so that the lowermost bars of the latter will rest on the lowermost bars of the larger truss members at right angles thereto.
6. A metal reinforcement for concrete decks and floors comprising longitudinal and transverse truss members of different sizes, each consisting of upper and lower horizontal bars connected by webs at opposite sides of the truss, the webs of the larger truss members being in the form of short rods bent V-shape with the ends extended to rest upon the lower bars of the truss, said upper and lower bars and webs of the longitudinal or main truss members being spaced apart to receive the smaller or lateral truss members between them; together with metal clips connecting the longitudinal truss members together in parallel by engaging the contiguous lower bars of said truss members.
7. In combination with a plurality of truss members each comprising upper and lower bars connected by webs at opposite sides of the truss, the adjacent truss members having bars in contacting relation, of a metal clip for clamping the truss members together consisting of a strip of spring steel bent at each end in the arc of a circle corresponding approximately to the circumference of the contacting bars, whereby said clip is sprung over the bars in clamping them together.
8. In combination with a plurality of truss members each comprising upper and lower bars connected by webs at opposite sides of the truss, the adjacent truss members having bars in contacting relation, of a metal clip for clamping the truss members together consisting of a strip of spring steel bent at each end in the arc of a circle corresponding approximately to the circumference of the contacting bars, whereby said clip is sprung over the bars in clamping them together, one end of the metal strip being turned outwardly to provide a gripping member for removing the clip.
9. A metal reinforcement for concrete decks and floors supported by floor beams, comprising channel bars welded to the beams and having laterally projecting side members or lips, plates supported on the floor beams with the ends of the plates locked in place by the side members or lips of the channel bars, and a metal reinforcement resting on the channel bars and consisting of longitudinal and transverse truss members of different sizes each consisting of horizontal bars connected by webs at opposite sides of the truss, the horizontal bars and webs of the longitudinal or main truss members being spaced apart to receive the transverse truss members between them to form a grid-like reinforcement.
10. A metal reinforcement for concrete decks and floors supported by floor beams, comprising channel bars having holes through the bottom thereof for welding said channel bars to the floor beams and laterally projecting side members or lips spaced from the beams, the holes through the bottom of the channel bars providing for welding them to the beams, plates supported on the floor beams and having their ends locked in place by the side members or lips of the channel bars; together with a metal reinforcement resting on the channel bars and consisting of horizontal bars connected by webs at opposite sides of the truss, the horizontal bars and webs of the longitudinal or main truss members being spaced apart to receive the transverse truss members between them to form a grid-like reinforcement.
11. A metal reinforcement for concrete decks and floors supported by floor beams, comprising channel bars welded to the beams and having laterally projecting side members or lips, plates supported on the floor beams and having spaced apart corrugations or outwardly bulged portions at the opposite ends and intermediate portions thereof, said plates being locked in place on the floor beams by engagement of the laterally projecting side members or lips of the channel bars; together with a metal reinforcement resting on the channel bars above the plates.
12. In combination with a metal reinforcement for concrete decks and floors comprising truss members of different sizes adapted to be passed one series through the other transversely, channel bars having laterally projecting side members or lips, and corrugated metal plates having outwardly bulged portions extending the width of the plate at the opposite ends thereof for overlapping engagement of a series of plates one with another and for overlapping engagement of the channel bar with the opposite ends of the plates.
